Primary Examiner — Daniel D Bui*Assistant Examiner* — Andrew Kerr(74) *Attorney, Agent, or Firm* — Hahn Loeser & Parks LLP(57) **CLAIM**

The ornamental design for a travel mug, as shown and described.

DESCRIPTION

FIG. 1 is a front elevational view of a travel mug according to the concepts of the present invention;

FIG. 2 is a back elevational view of the travel mug shown in FIG. 1;

FIG. 3 is a left side elevational view of the travel mug shown in FIG. 1;

FIG. 4 is a right side elevational view of the travel mug shown in FIG. 1;

FIG. 5 is a top plan view of a lid, in a closed position, of the travel mug shown in FIG. 1;

FIG. 6 is a top plan view of a lid, in an open position, of the travel mug shown in FIG. 1; and,

FIG. 7 is a perspective view of a lid, in an open position, of the travel mug shown in FIG. 1.

The broken lines showing portion(s) of the travel mug are for the purpose of illustrating environmental structure only and forms no part of the claimed design.
